CLAIM

We claim the ornamental design for a telephone body, as shown and described.

DESCRIPTION

FIG. 1 is the front perspective view of a telephone body showing our new design;

FIG. 2 is the front view thereof;

FIG. 3 is the rear view thereof;

FIG. 4 is the left-side view thereof;

FIG. 5 is the right-side view thereof;

FIG. 6 is the top plan view thereof;

FIG. 7 is the bottom plan view thereof; and,

FIG. 8 is a rear perspective view thereof.

The broken lines in the drawings depict portions of the telephone body that form no part of the claimed design; all

(Continued)

unshaded surfaces shown between the broken and solid lines
form no part of the claimed design.

1 Claim, 8 Drawing Sheets
